UNITED STATES PATENT OFFICE.

SAMUEL GAME, OF PITTSFIELD, MASSACHUSETTS, ASSIGNOR TO CROMPTON & KNOWLES LOOM WORKS, OF WORCESTER, MASSACHUSETTS, A CORPORATION OF MASSACHUSETTS.

TAKE-UP MECHANISM.

Application filed June 16, 1924. Serial No. 720,146.

This invention relates to take-up mechanism for looms and more particularly to the change gear devices by which the number of picks taken up per inch may be varied.

It frequently happens that a loom is called upon to weave fabrics having a variety of picks per inch and it is necessary to change the gearing in each instance so that the advance of the fabric may be kept in step with the number of picks required. Where it is desired to use the same loom for weaving fabrics ranging anywhere from sixteen to two hundred picks per inch it has formerly been necessary to keep on hand a large number of change gears. Accordingly, the principal object of my present invention is to equip a loom with permanently attached devices which will simplify the changing and also reduce the number of gears which must be held in readiness for use as the demands of the loom require.

A more specific object of my invention is to introduce shifting gears between some regularly driven part of the loom and the take-up mechanism.

A further object of my invention is to provide for moving the shifting gears by means which will give a visual indication that the gears are in proper position.

A still further object of my invention is to provide shifting gears for the purpose mentioned which may be driven in either direction so that the cloth may be fed backwardly when picking out a mispick.

With these and other objects in view which will appear as the description proceeds, my invention resides in the combination and arrangement of parts hereinafter described and set forth in the claims.

In the accompanying drawing wherein one form of my invention is shown,

Fig. 1 is a side elevation of a loom having my invention applied thereto.

Fig. 2 is a detailed enlarged view showing the shifting gears and the manner in which they are mounted,

Fig. 3 is a rear view of the shifting gears looking in the direction of arrow 3, Fig. 2,

Fig. 4 is a longitudinal section on line 4-4 of Fig. 3, and

Fig. 5 is a fragmentary vertical section taken on line 5-5 of Fig. 2.

Referring more particularly to the drawing it will be seen that I have provided a loom side 10 on which is mounted a stud 11 to

support worm gear 12. A take-up roll 13 is driven by a gear 14 which meshes with a pinion 15 cooperating with pinion 16 fastened to the stud 11 and rotating with worm gear 12. Other gears 17 and 18 may be employed to drive gear 19 which is fixed to cloth roll 20. A worm 21 meshes with the gear 12 and is fixed to shaft 22 the forward end of which is received by bearing 23 and provided with hand wheel 24. For each revolution of shaft 22 the gear 12 will be moved the space of one tooth and the take-up roll will be given an advance movement the extent of which is determined by the ratio of the gears 14, 15 and 16.

Upright shaft 25 is driven by driving bevel gear 26 and the clutch mechanism indicated at 27, the latter being controlled by lever 28. Sliding on shaft 25 is a sleeve 29 having upper and lower bevel gears 30 and 31, respectively, rigid therewith and movable endwise through manually controlled lever 32. The matter thus far described is old and for a more complete description of the same reference may be had to Patent No. 810,680, 80 issued to Ryon Jan. 23, 1906.

My invention relates more particularly to the mechanism interposed between shaft 22 and the driving bevel gears 30 and 31. In carrying out my invention I provide a stand 40 bolted or otherwise secured to the loom frame and adapted to receive a cap or cover 41 which is fitted to the frame and held thereto as by bolts 42. Split bearings 43 and 44, respectively, are provided, one half of each bearing being on the stand 40 and the other half being on the cap 41. Bearing 43 receives shaft 45 to which is fastened gear 46 and a somewhat larger gear 47. These gears are located within the housing formed by the stand and its cap and are driven by means of bevel pinion 48 which is fastened to shaft 45 and positioned to mesh with one or the other of the driving bevel pinions 30 or 31 according to the position of lever 32. 95

Bearing 44 receives the rear end of shaft 22 and as shown in Fig. 4 the latter is provided with a key-way 49 which receives key 50. A gear 51 has a sleeve 52 formed integral therewith which is provided with a slot 53 to receive key 50 and permits said gear 51 to slide on the shaft 22. A second gear 54 is secured to the sleeve 52 by means of a second key 55, the gears 51 and 54 thus being secured together and moving in 110

unison. The gear 54 may be driven onto the sleeve 52 and spaced sufficiently from gear 51 to provide room for a control arm 56 the inner end of which fits loosely over the sleeve 52 and positioned by the said gears 51 and 54. The outer end of the arm 56 has pivoted thereto a handle 57 the under side of which has extending therefrom a lug 58 which is positioned to be received by one or the other of detents 59 and 60, respectively, formed in the cap 41. The detents open into a slot 61 which permits movement of arm 56 in a direction parallel to shaft 22. The gears 46, 47, 51 and 54 are so related that when lug 58 is in detent 59, large gear 47 will mesh with small gear 51 on shaft 22 and when the lug is in detent 60 the gears 46 and 54 will be in mesh. The latter gears are preferably formed with an equal number of teeth so that for each revolution of shaft 45 shaft 22 will be given one revolution while gear 47 may be made twice as large as gear 51 so that for each revolution of shaft 45 shaft 22 will be given two revolutions.

If the loom is to be used for weaving coarse fabric, gears 47 and 51 will be in mesh so that the change gears previously referred to will give the take-up roll a relatively fast movement, but if the fabric is finer with more picks to the inch, the device will be shifted so that gears 46 and 54 will be in mesh. In this way it is possible to get the same range of picks with half the number of change gears. When it is desired to shift the gears the handle 57 will be raised from the position shown in full lines, Fig. 3, to the position shown in dotted lines and the arm 56 moved so that lug 58 will fit into the other detent. In this way the weight of the lever holds the lug in such position as to prevent ac-

cidental sliding movement of the shifting gears.

From the foregoing it will be seen that I have provided a very simple set of shifting gears which make it possible to get a large variety of numbers of picks with a reduced number of change gears. It will also be noticed that if lug 58 is in an intermediate position between the detents the handle 57 will be held outwardly and thus give a visual indication that the shift gears are not in proper mesh.

Having thus described my invention it will be apparent that changes and modifications may be made therein by those skilled in the art without departing from the spirit and scope of the invention and I do not wish to be limited to the details disclosed herein, but what I claim is:

1. In a loom, a take-up mechanism, a driving shaft, a plurality of gears moving in relatively fixed planes, sliding gears one only of which is in mesh with one of the first named gears, and means to shift the latter gears, said means including a weighted member having a lug to cooperate with a plurality of notches to position said shifting gears with respect to the gears rotating in fixed planes.

2. In a loom, a take-up mechanism, a set of driving gears rotatable in relatively fixed planes, a set of shifting gears to cooperate one by one with one or another of the first named gears, a handle to move said shifting gears, and means to give said handle a different position when the gears are properly meshed from the position it occupies when the gears are improperly meshed.

In testimony whereof I have hereunto affixed my signature.

SAMUEL CAME.
